PRESSES FOR CUTTING BLANKS FROM SHEET MATERIAL

Frank Seabury II, Manchester, and Robert W. Bradley, Marblehead, Mass., assignors to United Shoe Machinery Corporation, Flemington, N. J., a corporation of New Jersey

Application February 11, 1954, Serial No. 409,670

14 Claims. (Cl. 164—23)

This invention relates to presses and more particularly to presses of the type commonly known as clicking machines, for use in cutting blanks from sheet material.

In clicking machines as heretofore constructed, there is provided a cutting bed, a beam or platen mounted upon a spindle at one side of the bed for movement across the cutting bed and arranged for reciprocation by power means toward and away from the bed for forcing a freely movable cutting die through the sheet material supported upon the bed in order to produce blanks. The cutting bed usually comprises a block of wood or a pad of rubber or other material which is rigid enough to support the sheet material against pressure applied by the platen, and, at the same time is penetrable by the cutting dies used so that the dies can be forced through the sheet material and into the block or pad a sufficient distance to insure a complete penetration of the material in producing blanks.

One difficulty which has been experienced, heretofore, is that the platen must be adjusted to a height above the cutting bed in its rest position for a given length of stroke so that upon operation of the platen the die will be forced completely through the material and into the block and at the same time will not penetrate the block to such an extent that the die will stick. Improper adjustment of the height of the platen for a particular length of stroke thus may result in the slowing of the cutting operations because of the necessity of prying a stuck die from the block. Deep penetration of the block also increases the wear thereof and frequently results in unsatisfactory cutting because of the forcing of the material into the block itself. On the other hand, if the platen does not move downwardly far enough the die will not be completely driven through the material resulting in incomplete separation of the blank from the material or in blanks having ragged edges.

In view of the foregoing, it is an object of the invention to provide an improved press, of the type referred to, in which the stroke of the platen is automatically controlled independently of the thickness of the material operated upon or the height of the dies used.

To this end and as shown there is provided a press in which there are a work support and a platen constructed and arranged for relative movement toward and away from each other in performing pressure applying operations upon sheet material, carried by the work support, to produce blanks by means of a die located between the work support and platen, together with means for effecting relative movement of the work support and platen toward each other, and means responsive to engagement of the die with the work support for arresting the relative movement of the work support and platen toward each other.

Preferably, and as shown, the work support comprises a cutting block having an electrically conductive portion and there are provided power means, for effecting relative movement of the work support and platen, controlled by an electric circuit which includes the work support. As shown, the platen is actuated by hydraulic mechanism

including a solenoid operated valve for controlling the direction of the flow of fluid to act upon a piston connected to a spindle upon which the platen is mounted. Preferably too, the solenoid is controlled by means of an electric circuit which passes through the platen, die, and the conductive block, so constructed and arranged that when the platen has forced the die through the work and into contact with the block the valve will be operated to effect movement of the platen in a direction away from the block.

This mechanism thus provides an automatic control for the length of stroke of the platen such that the platen is moved away from the block shortly after the penetration of the work by the die. Thus the platen will be caused to engage the die and force it through the work to complete the cutting action entirely independently of the thickness of the work or the height of the die.

Preferably, and as shown, the control circuit includes time delay elements whereby the action of the solenoid can be delayed sufficiently so that the platen will be effective to force the die a short distance into the block before movement of the platen away from the block is commenced. Thus the depth of penetration of the die can be adjusted for different kinds of work, or cutting blocks, or dies, if necessary, but once adjustment has been made for a particular run of blanks of given thickness, size, and material, no further adjustment of the machine is required. In this connection it is to be noted that if dies of different heights are used no adjustment of the height of the platen relatively to the block is necessitated. Furthermore, since penetration of the die into the block is closely controlled the block is not subjected to excessive wear and its life is considerably increased.

These and other features of the invention are disclosed in the following specification and the accompanying drawings and are pointed out in the claims.

In the drawings,

Fig. 1 is a side elevation, partly in section, of a portion of a press embodying one form of my invention and includes a diagrammatic view showing a solenoid valve control mechanism and an electric circuit therefor; and

Fig. 2 is a vertical cross section on an enlarged scale through a portion of the machine illustrating the relation of the work support to the die and work supported thereon.

The illustrated machine comprises a work support in the form of a cutting bed 10, Fig. 1, for supporting sheet material such as leather 12, cloth, paper, metal foil, or other material, to be operated upon by a freely movable die 14 to produce blanks. The die is forced through the material by a platen or beam 16 mounted upon a vertical spindle 18 at one side of the bed for swinging movement across the bed into operative position over the die and arranged for reciprocation toward and away from the bed in a pressure applying operation upon the die.

The platen is preferably reciprocated by hydraulic power means. To this end, the lower portion of the spindle 18 carries a piston 20 slidably mounted in a cylinder 22 having fluid passages 24 and 26 connecting upper and lower portions of the interior of the cylinder above and below the piston to a valve casing 28. The interior of the casing is connected to upper and lower fluid inlet passages 30 and 32 extending to a fluid supply source 34. The central portion of the valve casing is provided with a fluid exhaust passage 36. Within the valve casing is slidably mounted a valve 38 comprising a valve rod 40 carrying four pistons 42, 44, 46 and 48. The piston 42 is mounted at the upper end of the rod 40 and is operable to engage the upper end of the casing to limit upward movement of the valve. Piston 48 is located near the lower end of the rod and is operable to limit downward movement of the valve. The pistons 44 and 46

are located upon opposite sides of the exhaust passage 36 and are so spaced from each other that when the valve is up fluid flows from the source 34, through passage 32, into the casing between pistons 46 and 48, through passage 26 into the lower portion of the cylinder 22 thus to force the piston, spindle, and platen upwardly. At this time fluid from the upper portion of the cylinder is exhausted through passage 24, through the space between the pistons 44 and 46, and out the exhaust passage 36. By this means the platen 16 is normally maintained in position above the bed and spaced therefrom by a distance somewhat greater than the maximum height of the die used plus the maximum thickness of the work to be operated upon.

The platen is brought down upon the work as a result of moving the valve to its lower position. When this occurs fluid passes from the source 34 through passage 30, through the space between pistons 42 and 44, through the passage 24 into the upper portion of cylinder 22, causing downward movement of the piston. Fluid from the lower portion of the cylinder flows through passage 26, through the space between pistons 44 and 46 into the exhaust passage 36.

In the preferred operation of the machine the piston 20 does not descend to the bottom of the cylinder 22 to complete its maximum stroke but is arrested and its movement reversed by moving the valve again to its upper position as will be hereinafter described.

The valve is controlled by a solenoid 50 having a plunger 52 connected to the lower end of the valve rod 40. When the solenoid is energized the plunger is pulled downwardly to move the valve into its lower position resulting in downward movement of the piston and of the platen toward the work. When the solenoid 50 is deenergized the valve is returned to its upper position by a spring 54. When this occurs the movement of the platen is reversed as above described.

It is to be understood that the structure thus far described is typical and that other means for actuating the platen, such as mechanical means, might be employed. It is highly desirable, however, that the platen actuating means be responsive to a readily controlled member such as the solenoid here illustrated.

In the present instance it is proposed to operate the solenoid in such manner that the movement of the platen is reversed and the platen is then caused to move away from the work very quickly, that is, in tenths of seconds after the die has passed through the work and engaged the surface layer of the cutting bed. To accomplish this the solenoid is placed in a manually operable control circuit which is in turn controlled by a second circuit which when closed extends through the platen 16, die 14 and cutting bed 10 and is activated as a result of the operation of the platen itself.

The manually operable control circuit includes a switch 56 one side of which extends through a lead 58 to an A. C. power source 60. The other side of the switch through leads 62 and 64 extends to a coil 66 of a relay 68 in an automatic control circuit and thence through lead 70 back to the power source. A lead 72 connects the lead 62 to one end of the solenoid 50 the other end being connected to a contact 74 of a relay 76 also in the automatic control circuit. The relay 76 has an armature 78 normally held by a spring 79 in its illustrated position to bridge the contact 74 and a second contact 80 connected to the power source.

The circuit through the solenoid is operated by a handle 82, mounted upon a pin 84 at the outer end of the platen 16, and by which the platen can be swung about the axis of the spindle. The handle is slidable vertically of the pin and is normally held in raised position by a spring 86. The lower end of the handle is beveled at 88 and adapted to engage, when depressed, a push button 90 for closing the switch 56. Thus depression of the handle 86, at such time as the relay 76 is

closed, results in energization of the solenoid 50 to effect downward movement of the platen.

The automatic control circuit extends through the platen, die and cutting bed. As is customary, the platen and die are composed of metal such as iron, steel or aluminum, and are therefore electrically conductive. The bed 10, as shown in Fig. 2, comprises a plate 92 of aluminum or other electrically conductive metal to which is bonded a layer 94 of electrically conductive rubber or plastic constituting a cutting block or pad. The plate provides a stiff backing for the layer 94 and the layer itself provides support for the work which can readily be penetrated by the edges of the die. As an alternative construction a wood block coated with aluminum paint has been found to be satisfactory. The cutting bed 10 rests upon a sheet of insulating material 96, such as fiber board, which in turn rests upon a portion 98 of the machine frame.

The automatic control circuit includes a gas tetrode 20 tube, or thyratron 100, having a control grid 102 connected through a limiting resistance 104 and a lead 105 to the plate 92 of the cutting bed.

The cathode 106 is connected to one side of filament 108 and to a lead 110. Another lead 112 extends from 25 lead 110 to the platen 16 and is grounded to the frame at 114. A lead 116 extends from lead 110 to a filament current supply section 117 of the secondary 118 of a transformer 120, the primary 122 of which is connected to a 110 volt source 124 of alternating current. The 30 lead 105 is connected through a grid bias D. C. supply including a limiting resistor 126, lead 127, voltage dropping resistor 128 to a rectifier 130 and from thence by a lead 132 to one side of a plate current supply section 134 of the transformer secondary. The other side of the 35 section is grounded through lead 116. The leads 116 and 127 are connected by a voltage dropping resistor 136 and through a filter condenser 138. The plate circuit extends from the transformer section 134 through a rectifier 140 across contacts 142 of the relay 68, when 40 the armature 144 thereof is closed, and through a current limiting resistor 146, through a coil 148 of the relay 76, to the plate 150 of the tube 100. A filter condenser 151 connects the upper portion of the plate circuit to ground.

45 Bridging the relay coil 148 are a plurality of capacitors 152 each having one side connected to a lead 154 extending to one end of the coil 148, and the other side being connected to one of the contacts 156 associated with a curved switch arm 158 joined by a lead 160 to the other end of the coil 148. This switch arm first bridges the coil 148 with one capacitor. Added movement of the arm adds more capacitors into a parallel circuit where their capacities are added together, increasing the time required for building up the needed voltage 55 across the relay coil 148 to operate it. The capacitors 152 constitute a time delay device for delaying the flow of plate current through the coil 148 and provides selectively time-variable means by which deenergization of the solenoid 50 is controlled. The values of the capacitors are so chosen that a variable time delay, in operating the relay 76, of from about 5 to 200 milliseconds is obtainable. For example, each capacitor may have a value of 10 microfarads.

Thus by varying time of operation of relay 76 to open 60 the circuit through relay 66, the time at which the spring 54 may move the valve upwardly following engagement of the die with the cutting block, can be varied. As a result of this, depth of penetration of the die into the block can be controlled over a wide range.

70 In the operation of the machine, assuming the parts to be in the position shown in Fig. 1, when the starting handle 82 is depressed closing the switch 56, the coil 50 is energized effecting downward movement of the valve 38. Fluid then flows through passages 30 and 24 to the upper portion of the cylinder 22 forcing the piston 20

and the spindle 18 downwardly. Downward movement of the spindle causes movement of the platen 16 down into engagement with the die 14 and forces the latter through the material 12 to produce a blank.

Upon closing switch 56 current also passes through coil 66 closing relay 68 in the plate circuit. After the die passes through the material it engages the conductive upper surface of the bed 10 bringing the grid potential to ground or zero where the grid bias is less negative and the tube fires or becomes conductive. After a time delay of a few milliseconds dependent upon the capacity in the delay circuit, the voltage builds up across the coil 148 resulting in opening the relay 76 and the deenergization of the solenoid 50. When the relay opens, the spring 54 returns the valve 38 to its upper position and fluid flows through passages 32 and 26 into the lower portion of the chamber forcing the piston 20 upward with the result that the downward stroke of the platen is arrested and then the platen is moved in a direction away from the bed.

As long as the handle 82 is held down relay 68 remains closed which results in holding the circuit through relay contacts 74, 80 open, and the solenoid 50 remains deenergized thus preventing further operation of the platen. Release of the handle 82 opens the switch 56 and deenergizes the relay 68 with the result that switch armature 144 drops, opening the plate circuit and permitting the relay 76 to close the circuit through the solenoid 50. After release of handle 82 the switch 56 is opened and the parts return to the positions shown in Fig. 1, reset for a subsequent cycle of operation.

From the foregoing description it will be observed that the press is provided with a control for automatically limiting the stroke of the platen through means responsive to engagement of the die with the cutting block and, consequently, independently of the height of the die used. It will further be observed that the variable time delay relay for initiating actuation of the power means in arresting the platen provides for the control of the depth of penetration of the block by the die with the advantages above enumerated.

It is to be understood that the press of the invention herein described can be employed to produce blanks from sheet material which is either electrically conductive or non-conductive. When operations are to be performed on conductive sheet material such as tin or zinc foil the time delay is adjusted to a low value such that the mechanism for reversing movement of the platen is operated very shortly after contact of the platen with the die.

Having thus described our invention what we claim as new and desire to secure by Letters Patent of the United States is:

1. A press comprising a work support and a platen mounted for relative movement toward and away from each other, a cutting die located between the work support and platen, means for effecting relative movement of the work support and platen toward each other in performing a pressure applying operation of the die upon sheet material positioned upon the work support, to produce a blank, and means including an electric circuit operative upon engagement of the die with the work support for arresting relative movement of the work support and platen toward each other.

2. In a press having a work support and a platen arranged for movement toward and away from the support in producing pressure applying operations upon a freely movable cutting die located upon sheet material upon the support, the combination of power means for moving the platen, and means including an electric circuit operative upon electrical contact of the die with the support for controlling operation of the power means in moving the platen away from the support.

3. A machine for cutting sheet material comprising an electrically conductive cutting block for supporting

the material, a cutting die located with a cutting edge upon the material, power means for moving the die toward the block through the material, and means including an electric circuit through the die and cutting

5 block operative in response to engagement of the die with the block to reverse the movement of the power means.

4. A press comprising a cutting block, a freely movable die, a platen movable toward and away from the cutting block in producing pressure applying operations upon the die when the die is located upon sheet material supported by the cutting block, means for reciprocating the platen, means for initiating operation of the reciprocating means to move the platen toward the block, and means including an electric circuit through the platen, die and block operable in response to engagement of the die with the block for initiating operation of the reciprocating means to move the platen away from the block.

5. A press comprising a cutting block, a freely movable die, a platen movable toward and away from the cutting block in producing pressure applying operations upon the die when the die is located upon sheet material supported by the cutting block, means for reciprocating the platen, means for initiating operation of the reciprocating means to move the platen toward the block, means operable in response to engagement of the die with the block for initiating operation of the reciprocating means to move the platen away from the block, and electrical means for selectively varying the actuation of the last-mentioned initiating means in timed relation to the engagement of the die with the block for controlling the extent of movement of the platen toward the block.

6. A press comprising a work support, a die, a platen movable toward and away from the work support in producing pressure applying operations upon the die when the die is located upon sheet material on the work support, means for reciprocating the platen, means for initiating operation of the reciprocating means to move the platen toward the work support, and means including an electric circuit through the platen, die and work support operable in response to engagement of the die with the work support for initiating operation of the reciprocating means to move the platen away from the work support.

7. A press comprising a work support, a die, a platen movable toward and away from the work support in producing pressure applying operations upon the die when the die is located upon sheet material on the work support, means for reciprocating the platen, means for initiating operation of the reciprocating means to move the platen toward the work support, electrical means operable in response to engagement of the die with the work support for initiating operation of the reciprocating means to move the platen away from the work support, and means for selectively varying the actuation of the last-mentioned initiating means in timed relation to the engagement of the die with the work support for controlling the extent of movement of the platen toward the work support.

8. A press comprising a work support having an electrically conductive surface portion, a die, a platen mounted for movement toward and away from the work support in producing pressure applying operations upon the die when the die is located upon sheet material on the surface portion, the die and platen being composed of

65 electrically conductive material, power means for reciprocating the platen, manually controlled means for initiating operation of the power means to move the platen toward the work support, means for initiating operation of the power means to move the platen away from the work support, and means for actuating the last-mentioned initiating means subsequently to engagement of the die with the surface portion of the work support comprising an electric control circuit through the platen, die and surface portion.

9. A press comprising a work support having an elec-

trically conductive surface portion; a die, a platen mounted for movement toward and away from the work support in producing pressure applying operations upon the die when the die is located upon sheet material on the work support, the die and platen being composed of electrically conductive material, power means for reciprocating the platen, manually controlled means for initiating operation of the power means to move the platen toward the work support, means for initiating operation of the power means to move the platen away from the work support, means for actuating the last-mentioned initiating means subsequently to engagement of the die with the surface portion of the work support comprising an electric control circuit through the platen, die and surface portion, and means for selectively varying the actuation of the last-mentioned initiating means in timed relation to the engagement of the die with the surface portion of the work support.

10. A press comprising an electrically conductive cutting block, a freely movable die, a platen mounted for movement toward and away from the cutting block in producing pressure applying operations upon the die when the die is located upon sheet material supported by the block, the die and the platen being composed of electrically conductive material, power means for reciprocating the platen, manually controlled means for initiating operation of the power means to move the platen toward the block, means for initiating operation of the power means to move the platen away from the block, and means for actuating the last-mentioned initiating means subsequently to engagement of the die with the block comprising an electric control circuit through the platen, die and block.

11. A press comprising an electrically conductive cutting block, a freely movable die, a platen mounted for movement toward and away from the cutting block in producing pressure applying operations upon the die when the die is located upon sheet material supported by the block, the die and the platen being composed of electrically conductive material, power means for reciprocating the platen, manually controlled means for initiating operation of the power means to move the platen toward the block, means for initiating operation of the power means to move the platen away from the block, means for actuating the last-mentioned initiating means subsequently to engagement of the die with the block comprising an electric control circuit through the platen, die and block, and means for selectively varying the actuation of the last-mentioned initiating means in timed relation to the engagement of the die with the block.

12. A press comprising an electrically conductive cutting block, a die, a platen mounted for movement toward and away from the cutting block in producing pressure applying operations upon the die when the die is located upon sheet material supported by the block, the die and platen being composed of electrically conductive material, power means for moving the platen, a control element for the power means selectively movable into operative position to cause the power means to move

the platen toward the block or into operative position to cause the power means to move the platen away from the block, a solenoid for moving the control element into the first mentioned operative position, manually controlled means for energizing the solenoid, means for deenergizing the solenoid in response to the engagement of the die with the block comprising an electric circuit through the platen, die and block, and means for moving the control element into the second-mentioned operative position upon deenergization of the solenoid.

13. A press comprising an electrically conductive cutting block, a die, a platen mounted for movement toward and away from the cutting block in producing pressure applying operations upon the die when the die is located upon sheet material supported by the block, the die and the platen being composed of electrically conductive material, hydraulic means for reciprocating the platen, a valve for controlling the direction of movement of the platen, manually controlled means for initiating operation of the valve to effect movement of the platen toward the block, means for initiating operation of the valve to effect movement of the platen away from the block, and means for actuating the last-mentioned initiating means subsequently to engagement of the die with the block comprising an electric control circuit through the platen, die and block.

14. A press comprising an electrically conductive cutting block, a cutting die, a platen mounted for movement toward and away from the cutting block in producing pressure applying operations upon the die when the die is located upon sheet material supported by the cutting block, the platen and die being composed of electrically conductive material, hydraulic means for reciprocating the platen, a valve for the hydraulic means selectively movable into either of two positions for controlling the direction of movement of the platen, means for moving the valve into position to initiate movement of the platen toward the block including a solenoid, manually controlled means for initiating energization of the solenoid, automatic means for deenergizing the solenoid, means including an electric circuit through the platen, die and cutting block for initiating operation of the automatic means in response to engagement of the die with the cutting block subsequently to penetration of the sheet material, and means subsequently operable to move the valve into position to initiate movement of the platen away from the block.
